THREADED ANCHORED INSERT

Fredrick J. Jennings, Fullerton, Calif., assignor to Like Manufacturing Corporation, Santa Fe Springs, Calif.

Filed Nov. 18, 1971, Ser. No. 200,272

Term of patent 14 years

Int. Cl. D8—08

U.S. Cl. D8—272

FIG. 1 is a perspective view of my new design for a threaded anchored insert;

FIG. 2 is a side elevation view of the insert in the direction of lines 2—2 of FIG. 1;

FIG. 3 is an end view of the insert along lines 3—3 of FIG. 2;

FIG. 4 is a side elevation view of the insert along lines 4—4 of FIG. 2;

FIG. 5 is an end view in the direction of lines 5—5 of FIG. 4; and,

FIG. 6 is an interior view of the insert as sectioned along lines 6—6 of FIG. 3.

I claim:

The ornamental design for a threaded anchored insert, substantially as shown.
